Attorney.

UNITED STATES PATENT OFFICE.

FRANCES ANNIE PENNINGTON, OF STOCKPORT, ENGLAND.

ARM-SUPPORT FOR CRUTCHES AND THE LIKE.

1,247,143.

Specification of Letters Patent.

Patented Nov. 20, 1917.

Application filed January 20, 1917. Serial No. 143,485.

To all whom it may concern:

Be it known that I, FRANCES ANNIE PENNINGTON, a subject of the King of Great Britain, residing at Heaton Chapel, Stockport, in the county of Chester, England, have invented new and useful Improvements in Arm-Supports for Crutches and the like, of which the following is a specification.

My invention relates to improvements in 10 that type of armpit supports for crutches and the like which is provided with an air cushion and generally comprises a base, a cover secured thereto and a valve controlled air bag located inside the said cover.

15 The object of my invention is the provision of means whereby the said air cushion is rendered very secure on its base and not liable to be pressed over the sides thereof, so as to render the support always very 20 comfortable to the armpit.

I attain this object by the mechanism for example illustrated in the accompanying drawing, in which—

Figure 1 is a side view of the upper part of 25 the crutch with armpit partly in section, and Fig. 2 is an end view, and Fig. 3 a sectional plan of Fig. 2 on line 3—3, and Fig. 4 a cross section of Fig. 1 on line 4—4 of the armpit support. Fig. 5 is a side view 30 partly in section. Fig. 6 an end view, and Figs. 7 and 9 are cross sections, the former of Fig. 8 on line 7—7, and the latter of Fig. 1 also on line 4—4 with base shown secured to a wooden support. Fig. 8 a sectional 35 plan of Fig. 7 on line 8—8.

Similar letters refer to similar parts throughout the several views.

Referring to the figures generally, I form the base *a* of my improved armpit support 40 of metal with a downwardly extending flange *b* at each side and a hole in the middle for the air inlet valve *c* on the bag *d* to project through.

The cover *e* inclosing the air bag I make 45 of leather or other strong material with downwardly extending sides *f* adapted to be clamped to the flanges *b* of the base *a*.

I may form the cover *e* with ends *g* stitched thereto and having each a downwardly extending flap *h* adapted to be turned inwardly to rest upon the said base and thus make up the cover at the bottom for a short distance, see Figs. 1 and 2.

In lieu of the said formation I may form 55 each end *g* of the cover *e* with a circular

blocked flange *i*, see Fig. 5, adapted to fit into and be secured to the cover, say by stitching. In this case I may also form the side of each cover end with a downwardly extending flap *k* adapted to be clamped to 60 the flanges of the base which will hold the cover ends both laterally and longitudinally securely in position on the base.

The sides of the cover *e* are securely clamped to the flanges *b* of the base *a* by a 65 plate *l* of metal or other suitable material placed upon the sides *f* of the cover *e* and by means of suitable screws *m* secured to the flanges *b* of the base *a*, see more particularly Figs. 1 and 3.

To prevent longitudinal displacement of the cover *e* I may form the sides *f* so as to permit of being drawn at the bottom around each end of the base *a*, see more particularly Fig. 3, while each end of the plate 70 *l* I bend inwardly to fit against the sides of the cover *e* drawn around and thereby grip them tightly.

In order to prevent the lateral displacement of pneumatic armpit supports, I use 80 plates *l* for securing the cover to the flanges *b* of the base *a* which have at each end a raised part *n*, which forms a lateral support for the cover *e* on the base *a*.

For the same purpose I may also provide 85 the cover with means which securely tie each side of the cover to the remote side of the base.

For example I secure to the interior of the cover *e*, see Figs. 7 and 8, at each side a 90 strip *o* having parts cut away to form a number of straps, tongues *p* or the like so disposed that the two strips can interpenetrate and each pass to the remote side of the base where they are clamped with the 95 cover *e* to the flanges *b* of the base *a* by means of plates *l*.

I may face the cover *e* with plush or the like soft material.

The armpit support described may be applied to any kind of old or new crutch.

If intended for a crutch with bifurcated upper end, I furnish the said base with two studs *q* which may be screw-threaded and are suitably secured into the said upper 105 ends, see Figs. 1, 2, 3, 4, 5 and 7. Referring to Fig. 9, if intended for a crutch with wooden armpit supports, I may by means of the screw-threaded studs *q* and nuts *r*, secure a plate *s* to the underside of the said 110

base α , which plate s projects from each side and is adapted to be suitably secured to the wooden support t .

I claim:

5. 1. In a crutch armpit support, a base having on each side a downwardly extending flange, an air bag seated on the said base, a cover around the said bag having downwardly extending sides fitting against the said flanges and a plate secured to each of the latter clamping thereto the said cover sides, for the purpose hereinbefore set forth.
10. 2. In a crutch armpit support, a base having on each side a downwardly extending flange, an air bag seated on the said base, a cover around the said bag having downwardly extending sides fitting against the said flanges and around the ends of the said base and a plate having each end inwardly bent to clamp the said cover sides both to the said flanges and ends of the said base, for the purpose hereinbefore set forth.
15. 3. In a crutch armpit support, a base having on each side a downwardly extending flange, an air bag seated on the said base, a cover around the said bag having downwardly extending sides fitting against the said flanges and a plate secured to each of the latter clamping thereto the said cover sides, the said plate having at each end upwardly extending means for laterally supporting the said cover, for the purpose hereinbefore set forth.
20. 4. In a crutch armpit support, a base having on each side a downwardly extending flange, an air bag seated on the said base, a cover around the said bag having downwardly extending sides and internally blocked ends with downwardly extending flaps fitting against the said flanges and a

plate secured to each of the latter clamping thereto the said sides and flaps, for the purpose hereinbefore set forth.

5. In a crutch armpit support, a base having on each side a downwardly extending flange, an air bag seated on the said base, a cover around the said bag having downwardly extending sides and internally at each side straps which interpenetrate and together with the said cover sides fit against the said flanges and a plate secured to each of the latter clamping thereto the said cover sides and straps, for the purpose hereinbefore set forth.

6. In a crutch armpit support, a base having on each side a downwardly extending flange, an air bag seated on the said base, a cover around the said bag having downwardly extending sides fitting against the said flanges and a plate secured to each of the latter clamping thereto the said cover sides and means depending from the underside of the said base for securing the armpit support to the crutch, for the purpose hereinbefore set forth.

7. In a crutch armpit support, a base having on each side a downwardly extending flange, an air bag seated on the said base, a cover around the said bag having downwardly extending sides fitting against the said flanges, a plate secured to each of the latter clamping thereto the said cover sides and means depending from the underside of the said base for securing the armpit support to the crutch, the said means carrying a plate fitting against the bottom edges of the said flanges and furnished at each side with holes for fastenings, for the purpose hereinbefore set forth.

FRANCES ANNIE PENNINGTON.
